UNITED STATES PATENT OFFICE.

CARLETON RUHE, OF NEW YORK, N. Y., AND FREDERIC R. BARKER, OF SALEM,
MASSACHUSETTS, ASSIGNEES, BY MESNE ASSIGNMENTS, TO RUHE TAN-
NING MACHINERY COMPANY, OF BOSTON, MASSACHUSETTS.

MACHINE FOR SCRUBBING, BRUSHING, AND CLEANSING LEATHER.

1,356,016.

Specification of Letters Patent. Patented Oct. 19, 1920.

Application filed June 13, 1919. Serial No. 304,070.

To all whom it may concern:

Be it known that we, CARLETON RUHE, a citizen of the United States, residing in the borough of Manhattan, city, county, and State of New York, and FREDERIC R. BARKER, a citizen of the United States, residing at the city of Salem, county of Essex, State of Massachusetts, have invented certain new and useful Improvements in Machines for Scrubbing, Brushing, and Cleansing Leather, of which the following is a specification, reference being had to the accompanying drawings, in which like numerals indicate corresponding parts in each of the several figures.

Our invention relates to certain improvements in that class of scrubbing and brushing machines illustrated in the prior patent of the above named Carleton Ruhe, No. 1,233,709, and the important object of the invention is to provide a machine of that character convenient in use, expeditious in operation, composed of a few simple parts and adapted to receive and hold the hide or stock during the cleansing operation and while being subjected to the action of the brushes thereon. Other objects and advantages of the invention will appear throughout the course of the description.

Referring to the drawings Figure 1 is a side elevation of a machine embodying our invention and Fig. 2 is a plan view with parts broken away and parts in section. For the purpose of illustration the drawings show a preferred embodiment of the invention, but it is to be understood that the form of said invention here shown is to be taken as a preferred type of the same and that various changes in the shape, size and arrangement of the several parts may be made or resorted to without departing from the spirit of the invention or the scope of the claims made thereon.

In the drawings the numeral 1 designates the supporting frame which is composed of vertical posts 2 and 3, 4 and 5 integrally and rigidly connected and held in position by longitudinal and transverse beams 6, 7, 8, 9 and 6^a, 7^a, 8^a and 9^a. Mounted rigidly within and upon this supporting frame 1 is a casing or tub 10 inclosing the several working parts of the machine, which is of sufficient size to accommodate the movement of the brush 26 from an idle position

as shown by the dot and dash lines in Fig. 55 1 to a position of contact with the drum 11.

The rotatable drum 11 is preferably situated in the lower part of this casing or tub 10, being sustained by means of the shaft 12 mounted on bearings 13 which 60 bearings are sustained by rods 14, held up by springs 15.

An endless conveyer belt 16 passes about the circumference of the drum 11 and also runs over an idler roller 17 which is carried 65 in a rocker 18, mounted on a pivot 19. The rocker 18 is adjustable in and out by means of the rod 20 screwed into the nut 21 to enable the conveyer belt 16 to be tightened 70 as desired about the drum 11. The pressure feed roll 22 runs on the surface of the drum 11 and is carried on the center bearings 23 of the machine, being driven by the chain 24 at the same surface speed with the drum 11, with which it holds contact. 75 This chain 24 passes over a sprocket mounted on the shaft 59 of the pressure feed roll 22 and also over a sprocket mounted on the shaft 39 of the clutch 40.

Upon the opposite sides of the pressure 80 feed roll 22 are cylindrical brushes 25 and 26 carried on roller bearings 27 and 28, which brushes also hold contact with the drum 11. Power is preferably applied by means of the pulley 29 through the shaft 85 30 of the brush 25 and is then distributed by means of the worm 31 and worm gear 32 to the shaft 33. This shaft 33 then distributes its power through the worm 34 and worm gear 35 to the drum 11. The power 90 of the shaft 33 is also delivered to the tube 36 through the agency of worm 37 and worm gear 38. The tube 36 then distributes its power to the shaft 39 through the agency of a clutch 40.

The operation of the mechanism of the clutch 40 is as follows: When the treadle 41 is pushed down it rocks the shaft 42 and in so doing swings the rocker arm 43 so as to disengage the cam knuckle 44 out of the face cam 45 and also with the same movement shoves the cone 46 in contact with the clutch finger 47 so as to give an outward movement to said clutch finger 47 in order to operate the clutch ring 48 with a contracting effect on said tube 36. When the clutch 40 is thus engaged with the tube 36, it drives the shaft 39 through the agency

of the set screw 49 which makes the said clutch 40 fast to the shaft 39. The power of the continuously driven tube 36 is thus transmitted to the shaft 39 until the face 5 cam 45 which is rigidly mounted on said shaft 39, revolves one-half revolution, at which time the shape of the face cam 45 allows the cam knuckle 44 to engage itself, thus allowing the swing rocker 43 to swing 10 in and bring the cone 46 away from the clutch finger 47 which by releasing the contracting clutch ring 48 from the continuously driven tube 36, again disconnects the power of said tube 36.

15 It will be seen that by depressing the treadle 41 a half revolution is given to the shaft 39 from the continuously driven tube 36. When the shaft 39 is thus revolved a half revolution it swings the cranks 78 20 which are fast upon said shaft 39 also though a half revolution. The cranks 78 are connected with the rocker or swing arms 79 by means of a composite connecting rod 50, which connecting rod 50 is composed 25 of a double diameter shaft 51 and a tube 52, the shaft 51 being adjustably held in the knuckle 53 and the tube 52 in the knuckle 54. Over the tube 52 is mounted a spring 30 55 which is held in position at one end by a disk 57 rigidly fastened to the shaft 51 and at the other end by adjustable nuts 58 upon the tube 52. The said shaft 51 is, as before mentioned, of double diameter, the larger diameter engaging the inside diameter of 35 the tube 52 and the smaller diameter running through a nut 75 screwed into the end of the tube 52 opposite to that end which is fastened to the connecting rod knuckle 54. Thus it will be seen that by adjusting the 40 nuts 58, additional pressure may be given to the spring 55 which will have a tendency to spread the tube 52 and the shaft 51 away from each other. The swing arms 79 are pivotally mounted on the shaft 59 of the 45 pressure feed roll 22 and on the opposite end of said swing arms 79 from the end to which said composite connecting rod 50 is pivoted is held the brush 26 in roller bearings 28.

The drive for the brush 26 is obtained as 50 follows:

On the shaft 30 of the brush 25, which is driven directly, is a chain sprocket 61, which, by means of a chain 62, drives a chain sprocket 63 idly running upon the shaft 59 of the pressure roll 22. This idle 55 chain sprocket 63 is integral with a gear 65 which meshes with a gear 66 held in a stud 67, mounted in a bearing 68 in the swing arms 79 midway between the center pivotal bearing 59 on the pressure feed roll 22 and the bearing 28 of the brush 26. Integral 60 with this gear 66 is a chain sprocket 70, which by means of a chain 71, drives a chain sprocket 72 rigidly fast to the shaft 73 of the brush 26, which shaft 73 is held in bear-

ings 28 at the end of the swing arms 79 as before mentioned.

Thus it will be seen that the brush 26, is driven from the shaft 30 of the brush 25; from the chain sprocket 61 through the 70 chain 62 to the chain sprocket 63; from the gear 65 to the gear 66; from the chain sprocket 70 through the chain 71 to the chain sprocket 72 fastened to the shaft 73 of brush 26, and hence, during the scrubbing of the hide, both the brushes 25 and 26 are continually revolving toward the feed roll 22 and in the opposite directions, as shown by the arrows.

The front brush 26 is brought into and 80 out of contact with the drum 11 in the following manner:

By referring to the description of the drive of the shaft 30, it will be remembered that by depressing the treadle 41 the shaft 39 is given a half turn through the means of the clutch mechanism. When the treadle 41 is thus depressed, the cranks 78 fastened upon the shaft 30 will revolve half a turn and will consequently give a throw to the composite connecting rod 50 which connects said cranks 78 with the swing arms 79 equal in amount of twice the eccentricity of the crank. The total of this throw is about 7". This throw of the composite connecting rod 95 50 is transmitted to the swing arms 79 as hereinbefore described. It will be seen, therefore, that because of the fact that the swing rocker 79 is pivotally mounted approximately in the center on the shaft of the pressure feed roll 22, a rocker effect is thus obtained and this rocker effect brings the brush 26 in and out of contact with the drum 11.

The machine is operated as follows: When 105 the machine is idle the brush 26 will be out of contact with the drum 11 as shown by the position indicated by the letter *a* in Fig. 1. The hide is then introduced between the pressure feed roll 22 and the drum 11, being 110 carried forward by the action of the endless conveyer belt 16. When the hide thus commences to feed itself, the operator depresses the treadle 41, thereby rocking the shaft 42 and setting the mechanism of the clutch 40 into operation, thus bringing the brush 26 down into contact with the drum 11 in the 115 position shown by the letter *b* in Fig. 1 and the scrubbing or cleansing of the hide is then commenced. The brush 26 is constantly scrubbing the hide as it passes through the machine and the brush 25 is again scrubbing it as it passes out. The conveyer belt 16 which passes over the drum 11 and the idler roller 17 insures the proper 120 feeding of the hide out of the machine. When the hide has been thus entirely fed through the machine the operator again depresses the treadle 41, thus allowing the brush 26 to automatically give way from 125 130

contact with the drum 11, and to resume and remain in its former idle position until the treadle is again depressed. The composite connecting rod 50 accommodates the variations in the thickness of the hide as it is subject to the action of the brushes during the course of the operation.

It is optional to use a suitable liquid preparation to aid in cleansing the hide 10 while being subjected to the action of the brushes 25 and 26, which liquid preparation may be supplied by a pipe or other means.

No means for the application of a liquid cleansing preparation to the hide are shown 15 in the accompanying drawings, but the same would be preferably supplied through a pipe or pipes situated in proximity to the rotatable brushes 25 and 26.

It will be observed that the brush 25 and 20 the feed roll 22 are driven clockwise, while the brush 26 and the drum 11 carrying the endless conveyer belt 16 are driven counter-clockwise. Thus the hide will be engaged by the conveyer belt 16 carried on the circumference 25 of the drum 11 and running over the idler roller 11 and then brought into contact with the brush 26 when the treadle 41 is depressed and the action of the brush 26 will then assist in feeding the hide 30 which is brought into contact with the pressure feed roll 22 which serves to clamp the hide to the conveyer belt 16; the action of the pressure feed roll 22 and the brush 26 then serve to carry the hide forward and to 35 discharge the same from the machine when the scrubbing operation is completed. Any suitable liquid cleansing preparation may be applied to the hide during its travel through the machine and in any suitable or 40 preferred manner.

The invention is not restricted to the use 45 of a conveyer belt, as the same could be omitted and the drum itself, without such belt, utilized. The conveyer belt will, however, greatly aid in the success of the operation. In some of the claims hereafter made, the mention of the conveyer belt will be omitted and the claims made for the drum alone.

50 Having described our invention, what we claim and desire to secure by Letters Patent is:

1. In a machine for scrubbing, brushing or cleansing leather, a rotatable drum 55 mounted upon a frame, a conveyer belt running over said drum and over an idler roller, a pressure feed roll arranged in proximity to the drum, a pair of rotatable brushes supported by the frame in proximity 60 to and on opposite sides of the feed roll, the shaft of one brush being adapted to receive power from an outside source, a worm and worm gear by means of which the power is transmitted from the said brush shaft to another shaft, which again distributes its

power through a worm and worm gear to a continuously driven tube, the power of said continuously driven tube being in turn distributed to another shaft by the agency of a clutch mechanism, whereby a crank attached thereto is operated by the action of a treadle in order to obtain a rocker effect upon pivotally mounted swing arms carrying the second brush whereby said second brush is moved into and out of contact with the drum, and means for feeding the hide automatically.

2. In a machine for scrubbing, brushing or cleansing leather, a frame, a rotatable drum supported by the frame, a feed roll 80 connected with the frame and holding contact with the drum, two rotatable brushes oppositely disposed upon the intake and discharge sides of the feed roll, swinging arms pivotally mounted upon the shaft of the feed roll, one end thereof being attached to a connecting rod composed of a double diameter shaft and a tube both adjustably held in knuckle joints, the opposite end of said swing arms sustaining the intake brush 85 so as to swing the said brush into and out of contact with the drum, a crank attached to the connecting rod on the end opposite said swing arms, said crank being mounted upon a shaft rotated by means of power 90 transmitted from a continuously driven tube attached to said shaft, said tube being provided with a contracting ring operated by a clutch finger moved in and out by a cone operated by a rocker arm adapted to disengage a cam knuckle and face cam, said rocker arm being mounted upon a shaft 95 which is rocked by the action of a treadle.

3. In a machine for brushing, scrubbing or cleansing leather, a frame, a rotatable 105 drum mounted on a shaft in bearings, means for supporting said bearings yieldingly, a feed roll sustained by said frame in proximity to the drum upon the center bearings of the machine driven by a chain or other 110 means at the same surface speed as the drum, a rotatable brush in roller bearings disposed upon the discharge side of the feed roll in contact with the drum, another rotatable brush in roller bearings disposed 115 upon the intake side of the feed roll, being out of contact with the drum when in an idle position, said intake brush being mounted at one end of swing arms pivotally mounted on the center bearings of the machine, the other end of said swing arms being joined by a knuckle to a composite rod connecting said arms to cranks mounted upon a shaft rotated by the operation of a treadle and clutch through a continuously 120 driven tube operated by a clutch ring and clutch finger in coöperation with a rocker arm, face cam, cam knuckle and cone.

4. In a machine for scrubbing, brushing or cleansing leather, a frame, a casing 130

mounted on the frame inclosing a rotatable drum sustained by a shaft mounted on bearings yieldingly sustained, a feed roll having contact with the drum mounted on the center bearings of the machine, a rotatable brush disposed in roller bearings upon the discharge side of the feed roll mounted on a shaft sustained by the frame and having contact with the drum, a second rotatable brush in roller bearings disposed upon the intake side of the feed roll out of contact with the drum, a pair of swing arms pivotally mounted, one end thereof being rigidly attached to said intake brush and the opposite end of said arms being connected by means of a rod with cranks mounted on a shaft adapted to be revolved a half revolution by the movement of a clutch, means for operating said clutch whereby a throw will be given to the rod connecting the cranks with the swing arms, thereby causing the said swing arms to be rocked and the intake brush to be brought into and away from a position of contact with the drum.

5. In a machine for scrubbing, brushing or cleansing leather, a rotatable drum, a feed roll, a swing arm or rocker pivotally mounted on the shaft of the feed roll, a rotatable brush disposed in roller bearings on the intake side of the feed roll carried by one end of said swing arm, the other end of the swing arm being connected by means of a rod with cranks mounted on a shaft 30 to which a clutch is rigidly fastened, means for operating said clutch by a treadle whereby a rocker movement is imparted to the swing arm, causing the brush carried on the end of the swing arm to be brought into and 35 out of contact with the drum, a second rotatable brush disposed in roller bearings upon the discharge side of the feed roll held in contact with the drum, and automatic means for feeding the hide between the 40 drum and the feed roll.

6. In a machine for scrubbing, brushing or cleansing leather, a rotatable drum supported by a frame, a feed roll also supported by the frame, a rotatable brush connected with the frame disposed in roller bearings on the intake side of the feed roll, swing arms pivotally mounted, one end of said arms engaging and carrying said intake brush, the opposite end thereof engaging a rod connecting said swing arms with cranks rigidly mounted on a shaft operating a half revolution by means of a treadle and clutch mechanism, whereby said cranks are made to impart a throw to the connecting rod 50 causing the pivotally mounted swing arms to move the said intake brush into and out of contact with the drum, a second rotatable brush also sustained by the frame disposed in roller bearings upon the discharge side 55 of the feed roll, the same being mounted on

a shaft receiving power for the operation of the machine, and means for the transmission of the power from the shaft of the second brush to the drum and also to drive the intake brush, feed roll and drum.

7. In a machine for scrubbing, brushing or cleansing leather, a rotatable drum, a feed roll, a rotatable brush disposed on the intake side of the feed roll, swing arms pivotally mounted on the shaft of the feed roll, one end thereof carrying said brush and the opposite end engaging a composite rod connecting said swing arms with cranks operated by a treadle and clutch mechanism, the rod connecting said cranks being composed of a double diameter shaft and a tube adjustably held, means for spreading the tube and the said double diameter shaft of said connecting rod apart in order to allow for the variations in the thickness of hides, a second rotatable brush connected with the frame having contact with the drum, and means for rotating said brushes and for feeding the hide between the drum and the feed roll.

8. In a machine for scrubbing, brushing or cleansing leather, a rotatable drum, a feed roll, a rotatable brush disposed on the intake side of the feed roll, swing arms pivotally mounted on the shaft of the feed roll, one end thereof carrying said brush and the opposite end engaging a connecting rod uniting said swing arms to a crank rigidly mounted on a clutch shaft, said connecting rod consisting of a double diameter shaft and a tube, each adjustably sustained in knuckle joints, the larger diameter of said shaft engaging the inside diameter of the tube, the smaller diameter thereof running through a nut screwed into the opposite end of the tube, also of a spring mounted on the tube, and also means for giving additional pressure to said spring tending to spread the said shaft and the said tube away from each other, and a second rotatable brush having contact with said drum, and means for rotating said brushes and feeding the hide between the drum and feed roll.

9. In a machine for scrubbing, brushing or cleansing leather, a rotatable drum or feed roll, a rotatable brush disposed on the intake side of the feed roll, swing arms pivotally mounted on the shaft of the feed roll, one end thereof carrying said brush and the opposite end engaging a composite connecting rod connecting said swing arms with cranks operated by a treadle and a clutch mechanism consisting of a rocker shaft which is turned a half revolution by the action of said treadle, on which is mounted a rocker arm disengaging a cam knuckle out of a face cam and moving a cone into contact with a clutch finger; causing a clutch ring to be operated with a contracting effect

- upon a tube, thereby driving the shaft and imparting a rocker movement to said pivotally mounted swing arms by means of said cranks which are mounted on said shaft and 5 are so connected with said swing arms, and a second rotatable brush having contact with the drum, and, means for rotating said brushes and feeding the hide between the drum and feed roll.
- 10 10. In a machine for scrubbing, brushing or cleansing leather, and in combination, a supporting frame, a rotatable drum, a conveyer belt running over said drum, a feed roll in proximity to the drum, a rotatable 15 brush disposed in roller bearings on the discharge side of the feed roll in proximity to the drum, a swing arm or rocker pivotally mounted sustaining a second rotatable brush disposed in roller bearings on the intake 20 side of the feed roll, means for rotating said brushes and said drum and feed roll and for feeding the hide automatically between the drum and feed roll and means for bringing the second brush into and out of contact 25 with the drum, said means being controlled by the operation of a treadle and clutch adapted to impart a rocker movement to the swing arm through the agency of a crank connected with the swing arm.
- 30 11. In a machine for scrubbing, brushing or cleansing leather and in combination, a supporting frame, a casing, a rotatable drum mounted on a shaft in bearings, an endless conveyer belt passing around the circumference of the drum and also over an idler 35 roller carried in a pivotally mounted rocker, a feed roll mounted on a shaft having contact with the drum, a swing arm or rocker pivotally mounted on the shaft of the feed roll, a rotatable brush mounted in roller 40 bearings upon a shaft receiving power for operating the machine and disposed upon the discharge side of the feed roll in contact with the drum, a second rotatable brush attached to said swing arm mounted in roller 45 bearings upon a shaft disposed on the intake side of the feed roll, means for the transmission of power from the shaft of the first brush, a clutch mechanism mounted on a shaft rocked a half revolution by the movement of a treadle attached thereto by means of which a crank mounted on said clutch shaft transmits a throw to a composite connecting rod uniting said cranks with said swing arms, causing said intake brush to be 50 brought in and out of contact with the drum, substantially as shown and described.
